Inventor.

Eli T. Starr

UNITED STATES PATENT OFFICE.

ELI T. STARR, OF PHILADELPHIA, PENNSYLVANIA, ASSIGNOR TO SAMUEL S. WHITE, OF SAME PLACE.

DESIGN FOR A DENTIST'S UPPER-IMPRESSION TRAY.

Specification forming part of Design No. 5,194, dated August 8, 1871.

To all whom it may concern:

Be it known that I, ELI T. STARR, of the city of Philadelphia, in the State of Pennsylvania, have invented and produced a new and original Design for a Dentist's Upper-Impression Tray, of which the following is a specification:

The nature of my design is fully represented in the accompanying photographic illustrations, to which reference is made; and consists of a dip or depression, *a*, made in each of the two side edges of the tray to receive the malar prominences of the upper jaw, and also of a depres-

sion, *b*, in the middle of the front edge, to avoid the labial frenum. The handle *c* is made longer than heretofore, and to extend in a downward direction below the line of the base of the tray, as represented in the illustration.

I claim as my invention—

The design for a dentist's upper-impression tray, as shown.

ELI T. STARR.
